[57] CLAIM

The ornamental design for a leaf container, as shown and described.

DESCRIPTION

FIG. 1 is a front elevational view of the leaf container of the present invention;

FIG. 2 is a rear elevational view of the leaf container of FIG. 1;

FIG. 3 is a left side elevational view of the leaf container of FIG. 1, the right side elevational view being a mirror image thereof;

FIG. 4 is a top plan view of the leaf container of FIG. 1;

FIG. 5 is a bottom plan view of the leaf container of FIG. 1;

FIG. 6 is an exploded top, front, left side perspective view of the leaf container of FIG. 1; and,

FIG. 7 is a cross sectional view of the leaf container of FIG. 1 along line 7—7 of FIG. 5.
